G. H. GILMAN

DRILLING MACHINE

Filed July 18, 1921

UNITED STATES PATENT OFFICE.

GEORGE H. GILMAN, OF BELMONT, MASSACHUSETTS.

DRILLING MACHINE.

Application filed July 18, 1921. Serial No. 485,707.

My invention relates to drilling machines and particularly but not exclusively is concerned with the moving of the tool of such a machine relatively to the work.

5 My invention will be best understood from the following description when read in the light of the accompanying drawings of a specific embodiment of my invention selected for illustrative purposes while the scope of 10 my invention will be more particularly pointed out in the appended claims.

In the drawings:—

Fig. 1 is an elevation with parts broken away of a machine constructed according to 15 my invention;

Fig. 2 is a view on an enlarged scale with parts in section and showing a detail of the machine;

Figs. 3, 4, 5 and 6 respectively are sections on the lines 3—3, 4—4, 5—5 and 6—6 of Fig. 1.

Referring to the drawings, I have shown a drilling tool 1, and an actuator 3 for said tool; and although these may be of any suitable or usual type, as shown I have indicated the tool as a rock drill steel and its actuator as a fluid pressure operated hammer drill.

For feeding the tool relative to the work 30 I herein provide a feed cylinder 5, the feed cylinder and actuator as shown being arranged side by side and secured together in any suitable manner so that motion of the feed cylinder will be imparted to the actuator and hence to the tool. As will be understood by those skilled in the art, the actuator may comprise front and rear heads or casing sections 7, which are secured in assembled relation with the cylinder section or 40 other sections of the casing by means of side bolts 9, of which I have shown four. As shown the feed cylinder 5 at opposite ends is provided with pairs of oppositely arranged perforated ears 11 through the perforations of which extend the projecting ends of the side bolts adjacent the feed cylinder.

As illustrated, fitting the interior of the feed cylinder I provide a feed piston which 50 comprises the piston proper or head 13 and the hollow cylindrical piston rod or stopping bar 15. If desired, the bar 15 may be of the same exterior diameter as the head 13 but as shown I have formed the bar of lesser diameter in order to provide the annular chamber 17 at the rear of the feed

cylinder. The bar 15 extends through the rear feed cylinder head 19, and in a manner hereinafter described is releasably secured to a suitable support herein exemplified by 60 the arm 21 carried by the mine column 23.

Extending through the front feed cylinder head 25 is a cylindrical bar 27 of smaller diameter than the feed piston and telescopically arranged therewith. As 65 shown, the piston is provided with the cylindrical bores 29, 30 and 31. The bar 27 fits the bore 29 and at the end of the bar is secured a head 33 fitting the bore 31. The bore 30 is of diameter intermediate 70 that of the bores 29 and 31 to provide a stop shoulder 35 for the head 33 and a conduit 37 which conduit as shown by Figs. 1 and 3 is placed in permanent communication with the atmosphere by means of a port 39. The port 39 is located a distance from the head 13 approximately equal to the length of the feed cylinder so that irrespective of the relative positions of the piston and feed cylinder, the air which leaks 75 around the packing 41 carried by the head 13 and around the packings 42 carried by the head 33 will pass through the conduit 37 into the atmosphere by means of the port.

As shown the end of the bar 27 is provided with a point 43 for engaging the rock or other work, and for causing this action I herein connect the end of the bar 15 with an air hose 45 or other source of pressure fluid, the admission and exhaust of which fluid to and from the interior of the bar 15 is controlled by means of a three-way valve 47. When pressure fluid is admitted into the interior of the bar 15 and the latter is secured to its support, said fluid acting on the rearward face of the head 33 will force the point 43 firmly against the work and thus provide a rigid structure along which the cylinder may be moved.

For supporting the bar 15 I have shown an attachment having two approximately semi-cylindrical halves 49 and 51 adapted to be clamped to the arm 21 by means of the bolts 53. The upper half of the attachment has integrally formed therewith at 100 one side thereof a collar 55 which surrounds and slidably fits the bar 15. Integrally formed with the opposite side of the half 51 is a jaw 57, and pivoted at 61 to one end of this jaw is a cooperating jaw 59. These 105 jaws are formed with semi-cylindrical recesses which fit the bar 15 and thus form

a clamp for securing the bar to the attachment. For operating the clamp I have shown a screw 63 extending through the ends of the jaws remote from the pivot and threadedly engaging the jaw 57, said screw having the shoulder 65 engaging the upper face of the jaw 59. In an obvious manner, by turning the screw by its operating handle 67, the bar 15 may be fixedly secured to the attachment, or released therefrom and slid through the collar 55.

Herein, for causing the feed cylinder to move the tool toward the work I admit pressure fluid to the chamber 69 of the feed cylinder, and for moving the tool away from the work I admit pressure fluid to the chamber 17 of the feed cylinder. For this purpose, I have shown in the feed cylinder wall, passages 71 and 73 respectively communicating at one end with the interior of the cylinder adjacent its forward and rearward ends, and at their opposite ends respectively communicating with the sockets 75 and 77 formed in the cylinder wall. On the side of the actuator adjacent the cylinder I have shown a pair of nipples 79 which enter the sockets and fit therewith in a fluid-tight manner. The actuator I have shown connected with a source of fluid pressure by means of an air hose secured to the air hose connection 81, and in the rear cylinder head 7 I have shown a four-way valve 83 having the operating handle 85 and a valve casing forming a valve chamber 86 in permanent communication with a passage 87 supplied from the air hose connection. Herein this valve is arranged optionally to connect the passages 71 and 73 of the feed cylinder alternately to the air supply and the atmosphere. For this purpose the valve, which may be in the form of the usual turning plug, is herein provided with an arcuate groove 89 in permanent communication with the passage 87 and with an axial passage 91 leading to the end of the valve stem so as to be in permanent communication with the atmosphere. In the same plane as the groove 89 the valve is shown as provided with a radial passage 93 leading from the axial passage 91 to the groove 92 on the exterior of the valve. The actuator rear cylinder head 7 is shown as provided with an inner member 95 having an exterior cylindrical surface which in a fluid tight manner fits the body portion of the head and about which are formed two grooves 97 for establishing communication between, respectively, passages 99 and 101 leading to the valve casing and passages 103 and 105 formed through the nipples and in communication with the sockets the nipples fit. In this manner the passage 99 is in permanent communication with the rear feed cylinder chamber 17 and the passage 101 in permanent communication with the forward feed cylinder chamber 69.

The operation of parts so far described is as follows:—

With the parts in the position shown by Fig. 2, air is exhausted from both ends of the feed cylinder by way of the groove 92 70 which in said position communicates with both passages 99 and 101. If the valve is turned clockwise from the position of Fig. 2 to move the groove 92 out of communication with the passage 101 and the groove 89 75 into communication with the passage 101, pressure fluid will be admitted to the forward end of the feed cylinder, while the rearward end will be connected to the atmosphere. This will cause the feed cylinder to move toward the work to advance the drilling tool up to the work, after which the actuator may be put into operation to cause the hole to be drilled, the feed cylinder feeding the drill and its actuator during the drilling operation. If it should be desired to withdraw the drill steel from the hole the valve will be moved in a counterclockwise direction past the position illustrated by Fig. 2, to move the groove 92 out of communication with the passage 99 and the groove 89 of the valve into communication with the passage 99, which will exhaust the front end of the feed cylinder and admit motive fluid to the rear end, and thus cause the tool to be moved away from the work. When the feed cylinder has moved toward the work a distance equal to the feed travel, which travel is determined by the effective length of the feed cylinder, the valve may 95 be moved to the position of Fig. 2 and the screw 63 may be operated to release the bar 15 from its support, and the bar then be slid through the collar 55 toward the work to the opposite end of the feed cylinder, after 100 which the bar may be again secured to its support and the tool again be fed forward a distance equal to the length of the feed travel. This may be repeated until the tool has entered the work for its full length, after 105 which it may be withdrawn from the hole by reversing the operation just described, or, by moving the actuator away from the work, the tool may be removed from the chuck of the actuator, and the actuator then swung 110 out of line with the tool to permit the latter to be withdrawn manually.

For supporting the tool when the hole is being spotted, or when for other reasons this is necessary or desirable, I have shown means for suspending the portion of the tool remote from the actuator from the bar 27. For this purpose I have shown a clamp comprising the members 107 and 109 hinged together at 111 and having jaws 113 adapted to engage the bar 27. The lower portion of the members 107 and 109 I herein provide with the semi-cylindrical recesses 115, which when the jaws of the members engage the bar provide a cylindrical opening for loosely 125 130

supporting the tool. For causing relative movement between the members 107 and 109 I have shown a screw 117 threadedly engaging the member 109 and having an operating handle 119 providing a shoulder 121 abutting the outer surface of the member 107.

- In Figs. 1 and 2, I have shown a retarder for opposing motion of the feed cylinder or for clamping the feed cylinder to the bar 15.
- 5 As shown I provide a member 123 having a bore 125 fitting over the reduced diameter portion 127 of the rear feed cylinder head 19, and having an opening 129 fitting the bar 15. Holding the feed cylinder, the head 19 and the member 123 in assembled relation I herein provide bolts 131 passing through perforations in the ears 133 and 135 respectively carried by said member and feed cylinder. As illustrated the member 123 carries a sleeve 137 which is flexible and may be formed of a tubular section of interwoven fibers of asbestos and metal, being known to the trade as "Multabestos". The member 123 is shown as provided with a raised portion 25 139 having a screw-threaded opening receiving the screw 141, said screw being provided at one end with an operating handle 143, and at its opposite end provided with a head 145 secured to the screw and fitting the bore 30 147 of the enlargement 139. As shown the member 123 provides a chamber which surrounds the sleeve 137, and in said chamber is placed a suitable yieldable mass which, when the screw is operated to move the head 35 145 inwardly, will serve to compress the sleeve to cause the latter to grip the bar 15. This mass, hereinafter referred to as a "fluidic" mass, may be any substance or structure which has the properties of a fluid, as 40 for example, a liquid substance or granular structure. I have shown the mass as made up of small spheres, and providing for their insertion into the container afforded by the member 123 I have shown the wall thereof 45 as provided with an opening closed by the removable plug 149. It will be understood that the degree of gripping of the bar 15 by the member 37 may be regulated by means of the screw 141.
- 50 Although I have described for illustrative purposes one specific embodiment of my invention, it will be understood that wide deviations may be made therefrom without departing from the spirit of my invention.

55 Claims.

1. A drilling machine having, in combination, an elongated supporting part adapted to be supported at spaced points lengthwise thereof, a drill steel actuator arranged in 60 parallel relation to said part, means including a feed cylinder for slidably supporting said actuator on said part between said spaced points, said feed cylinder being rotatable about the axis of said part.

2. A drilling machine having, in combina-

tion, an elongated extensible supporting part adapted to be supported at spaced points lengthwise thereof, a drill steel actuator arranged in parallel relation to said part, means including a feed cylinder for slidably supporting said actuator on said part between said spaced points, said feed cylinder being rotatable about the axis of said part.

3. A drilling machine having, in combination, an elongated supporting part comprising a pair of oppositely extending telescopically arranged members each adapted to engage a support for rigidly supporting said part, a feed piston head carried by one of said members, a feed cylinder slidably and 80 rotatably mounted on said part and surrounding said piston head, and a drill steel actuator carried by said cylinder in parallel relation thereto.

4. In a drilling machine, a longitudinally arranged stationary support, a drill, actuator formed for carrying a drill, means for mounting said actuator on said support and providing for movement of said actuator along said support and for swinging of said 90 actuator out of line with the drill hole, said means comprising a cylinder on said support intermediate the length of said support, said cylinder carrying said actuator, and a piston adjustable lengthwise of said support cooperating with said cylinder.

5. In a drilling machine, a feed cylinder, a piston, connected relatively adjustable rods for supporting the machine extending through opposite ends of said cylinder, one 100 of said rods carrying said piston a drill actuator arranged to be moved by said cylinder, and means for admitting pressure fluid to said cylinder for moving it relatively to said piston.

6. In a drilling machine, a piston, a cylinder cooperating with said piston, a rod carrying said piston and extending through one end of said cylinder, means for supporting said rod, a second rod for support extending 110 through the opposite end of said cylinder and through said piston into the first named rod, a drill actuator arranged to be moved by said cylinder, and means for admitting actuating fluid into said cylinder.

7. In a drilling machine, telescopically arranged parts forming an extensible supporting member, a piston carried thereby at an intermediate portion thereof, a cylinder fitting said piston and member and being movable longitudinally thereof and rotatably mounted thereon, a drill actuator carried by said cylinder, means for admitting pressure fluid to said cylinder for moving it relative to said member, and means for locking 125 said cylinder in adjustable longitudinal and angular positions relative to said member.

8. In a drilling machine, telescopically arranged parts forming an extensible supporting member, a drill bit steel actuator, 130

- fluid pressure actuated means for moving said actuator along said member, and fluid pressure actuated means for extending said member.
5. 9. In a drilling machine, a drill actuator, telescopically arranged members adapted to be supported, means for releasably securing one of said members to its support, a feed piston and feed cylinder one of which is carried by one of said members and the other of which is arranged to move said actuator, and means for admitting pressure fluid to said cylinder.
10. 10. In a drilling machine, a bar carrying a piston, a bar telescopically arranged with the first mentioned bar, means for releasably securing said first mentioned bar to a support, a feed cylinder surrounding said piston and each bar, and a drill actuator carried by said cylinder.
15. 11. In a drilling machine, a bar carrying a piston, a bar telescopically arranged with the first mentioned bar, means for releasably securing said first mentioned bar to a support, a feed cylinder surrounding said piston and each bar, means for admitting fluid pressure to said first mentioned bar, and a drill actuator carried by said cylinder.
20. 12. In a drilling machine, a drill actuator, telescopically arranged members, one of which is adapted to engage the work, means for securing the other to a support, and means for moving said actuator along said members.
25. 13. In a drilling machine, a drill actuator, a feed cylinder for moving said actuator, a feed piston and piston rod, a rod extending into said feed cylinder and entering said piston and piston rod, means for causing said last named rod to be forced resiliently against the work, means releasably securing said piston rod to a support, and means for admitting pressure fluid to said cylinder.
30. 14. In a drilling machine, a drill actuator, a feed cylinder for moving said actuator, a feed piston and piston rod, a rod extending into said feed cylinder and entering said piston and piston rod, means for releasably securing said piston rod to a support, and means for admitting pressure fluid to said cylinder and to said piston rod, whereby said actuator may be moved relative to the work and the said second mentioned rod may be forced outwardly relative to said piston rod to bear against a support.
35. 15. In a drilling machine, a drill actuator and a feed cylinder secured together in side by side relation, a piston and piston rod for said cylinder, means for securing said rod to a support rearwardly of said cylinder, and means carried by said rod for engaging a support forwardly of said cylinder.
40. 16. In a drilling machine, a drill actuator and a movable feed cylinder secured together in side by side relation, a stationary piston and piston rod slidably and rotatably supporting said cylinder, a single valve carried by said actuator for admitting a pressure fluid to each end of said cylinder, conduits in said actuator and cylinder for conducting said pressure fluid, and cooperating sockets and nipples in the adjacent sides of said cylinder and actuator establishing communication between said conduits.
45. 17. In a drilling machine, a drill actuator and a movable feed cylinder secured together in side by side relation, passages in said cylinder leading to opposite ends thereof, a source of motive fluid supply connected to said actuator, passages provided by said actuator and in communication with said first named passages at the adjacent sides of said cylinder and actuator, and a controlling valve carried by said actuator for connecting the passages provided by said actuator to a source of pressure fluid supply.
50. 18. The combination with a stoper having a tool actuator and a feeding device comprising relatively movable cylinder and piston members, one of which members is connected to said actuator to move the latter, of means for releasably securing the other member to a support; said means and last named member providing that after the actuator has been moved the effective length of the cylinder said member may upon release of said means, be moved relative to said support and the work to permit the feeding device again to operate to move said actuator in the same direction.
55. 19. The combination with a tool actuator of a feed cylinder and a feed piston, means providing for movement of said actuator when said cylinder moves, and means for releasably securing said feed piston to support, whereby after the feed cylinder has been moved relative to the work said piston may be released from said support and moved through said cylinder in the same direction as that in which the cylinder has been moved, and the feed cylinder may again be moved in the same direction.
60. 20. In a drilling machine, a drill actuator, a feed cylinder and piston for moving said actuator, a bar for supporting said machine and extending through opposite ends of said cylinder, and means for supporting said bar.
65. 21. A drilling machine having in combination, a longitudinally extending member for supporting said machine, a cylinder mounted on said member for relative rotative and longitudinal movement, a piston carried by said member and cooperating with said cylinder, means for admitting pressure fluid to said cylinder, a drill actuator carried by said cylinder with the axis of said actuator parallel to the axis of said mem-

ber, said actuator adapted for carrying a drill steel coaxial therewith, and manually operable means carried by said cylinder for gripping said member. ⁴⁵

5 22. A drilling machine having in combination, a longitudinally extending member for supporting said machine, a cylinder mounted on said member for relative rotative and longitudinal movement, a piston carried by said member and cooperating with said cylinder, means for admitting pressure fluid to said cylinder, a drill actuator carried by said cylinder with the axis of said actuator parallel to the axis of said member, said actuator adapted for carrying a drill steel coaxial therewith, and manually operable means carried by said cylinder for gripping said member, said last named means comprising a sleeve surrounding said member and fluidic material for compressing said sleeve. ⁵⁰

10 23. A drilling machine having in combination, a longitudinally extending member for supporting said machine, a cylinder mounted on said member for relative rotative and longitudinal movement, a piston carried by said member and cooperating with said cylinder, means for admitting pressure fluid to said cylinder, a drill actuator carried by said cylinder with the axis of said actuator parallel to the axis of said member, said actuator adapted for carrying a drill steel coaxial therewith, and means carried by said cylinder for frictionally gripping said member. ⁵⁵

15 24. A drilling machine having in combination, a longitudinally extending member for supporting said machine, a cylinder mounted on said member for relative rotative and longitudinal movement, a piston carried by said member and cooperating with said cylinder, means for admitting pressure fluid to said cylinder, a drill actuator carried by said cylinder with the axis of said actuator parallel to the axis of said member, said actuator adapted for carrying a drill steel coaxial therewith, and means carried by said cylinder for frictionally gripping said member. ⁶⁰

20 25. A drilling machine having, in combination, a supporting part comprising a pair of telescopically arranged members one of which carries a piston head, a feed cylinder surrounding said members and head and having cylinder heads at opposite ends through which said members respectively project, a drill actuator carried by said cylinder in parallel relation thereto, and means carried by the member projecting through the head at the forward end of said cylinder for supporting a drill steel. ⁶⁵

26. A drilling machine having, in combination, a supporting part comprising a pair of telescopically arranged members one of which carries a piston head, a feed cylinder surrounding said members and head and having cylinder heads at opposite ends through which said members respectively project, a drill actuator carried by said cylinder in parallel relation thereto, and means carried by the member projecting through the head at the forward end of said cylinder for rotatably supporting a drill steel. ⁷⁰

27. A drilling machine having, in combination, a supporting part comprising a pair of telescopically arranged members one of which carries a piston head, a feed cylinder surrounding said members and head and having cylinder heads at opposite ends through which said members respectively project, a drill actuator carried by said cylinder in parallel relation thereto, said actuator for carrying the shank of a drill steel, and a support for the drill steel forward of the front end of said actuator. ⁷⁵ ⁸⁰

In testimony whereof, I have signed my name to this specification. ⁸⁵

GEO. H. GILMAN.

- ber, said actuator adapted for carrying a drill steel coaxial therewith, and manually operable means carried by said cylinder for gripping said member. 45
- 5 22. A drilling machine having in combination, a longitudinally extending member for supporting said machine, a cylinder mounted on said member for relative rotative and longitudinal movement, a piston carried by said member and cooperating with said cylinder, means for admitting pressure fluid to said cylinder, a drill actuator carried by said cylinder with the axis of said actuator parallel to the axis of said member, said actuator adapted for carrying a drill steel coaxial therewith, and manually operable means carried by said cylinder for gripping said member, said last named means comprising a sleeve surrounding said member and fluidic material for compressing said sleeve. 55
- 10 23. A drilling machine having in combination, a longitudinally extending member for supporting said machine, a cylinder mounted on said member for relative rotative and longitudinal movement, a piston carried by said member and cooperating with said cylinder, means for admitting pressure fluid to said cylinder, a drill actuator carried by said cylinder with the axis of said actuator parallel to the axis of said member, said actuator adapted for carrying a drill steel coaxial therewith, and means carried by said cylinder for frictionally gripping said member. 60
- 15 24. A drilling machine having in combination, a longitudinally extending member for supporting said machine, a cylinder mounted on said member for relative rotative and longitudinal movement, a piston carried by said member and cooperating with said cylinder, means for admitting pressure fluid to said cylinder, a drill actuator carried by said cylinder with the axis of said actuator parallel to the axis of said member, said actuator adapted for carrying a drill steel coaxial therewith, and means carried by said cylinder for frictionally gripping said member. 65
- 20 25. A drilling machine having in combination, a supporting part comprising a pair of telescopically arranged members one of which carries a piston head, a feed cylinder surrounding said members and head and having cylinder heads at opposite ends through which said members respectively project, a drill actuator carried by said cylinder in parallel relation thereto, and means carried by the member projecting through the head at the forward end of said cylinder for supporting a drill steel. 70
- 25 26. A drilling machine having, in combination, a supporting part comprising a pair of telescopically arranged members one of which carries a piston head, a feed cylinder surrounding said members and head and having cylinder heads at opposite ends through which said members respectively project, a drill actuator carried by said cylinder in parallel relation thereto, and means carried by the member projecting through the head at the forward end of said cylinder for rotatably supporting a drill steel. 75
- 30 27. A drilling machine having, in combination, a supporting part comprising a pair of telescopically arranged members one of which carries a piston head, a feed cylinder surrounding said members and head and having cylinder heads at opposite ends through which said members respectively project, a drill actuator carried by said cylinder in parallel relation thereto, said actuator for carrying the shank of a drill steel, and a support for the drill steel forward of the front end of said actuator. 80
- 35 28. A drilling machine having, in combination, a supporting part comprising a pair of telescopically arranged members one of which carries a piston head, a feed cylinder surrounding said members and head and having cylinder heads at opposite ends through which said members respectively project, a drill actuator carried by said cylinder in parallel relation thereto, said actuator for carrying the shank of a drill steel, and a support for the drill steel forward of the front end of said actuator. 85
- 40

In testimony whereof, I have signed my name to this specification.

GEO. H. GILMAN.

CERTIFICATE OF CORRECTION.

Patent No. 1,632,400.

Granted June 14, 1927, to

GEORGE H. GILMAN.

It is hereby certified that error appears in the printed specification of the above numbered patent requiring correction as follows: Page 3, line 86, claim 4, strike out the comma after the word "drill"; same page, line 101, claim 5, after the word "piston" insert a comma; line 130, claim 8, strike out the word "bit"; page 4, line 98, claim 18, after the word "may" insert a comma; page 5, line 32, claim 23, for the misspelled word "therewith" read "therewith"; and that the said Letters Patent should be read with these corrections therein that the same may conform to the record of the case in the Patent Office.

Signed and sealed this 12th day of July, A. D. 1927.

Seal.
